UNITED STATES PATENT OFFICE

FRITZ LIERS, OF BERLIN-LICHTENBERG, GERMANY

CASTING MOLD

Application filed November 15, 1926, Serial No. 148,549, and in Germany November 25, 1925.

This invention refers broadly to sectional, adjustable casting molds, and it is one of the important objects of the invention to provide means of setting the mold by means of levers and link connection, to accommodate articles of different sizes and configurations and to produce a mold of variable, substantially square or rectangular outer cross sectional shape. It is another important object of this invention to provide means of enabling the operator to produce a negative and a positive copy of an original in one and the same mold by merely swinging the mold into another position; and it is also an object of this invention to obtain comparatively smooth castings and to remove and detach or smoothen any fins or undesired rough projections that may have been formed in the process of casting. Other objects and advantages will appear, as the specification proceeds and from an inspection of the accompanying drawings in which by way of exemplification one of the various possible embodiments of the principles of my invention is shown diagrammatically.

In the drawings:—Figure 1 is a front elevation of the device. Fig. 2 is a top plan view. Fig. 3 is a vertical longitudinal section of Figs. 1 and 2 turned through 90 degrees in order to show the operation and arrangement of the sprue or fin removing means. Fig. 4 is a vertical longitudinal section of the device when rotated 180 degrees about its horizontal axis. Fig. 5 is a top plan view of the device showing the mold walls in the position corresponding to the minimum size of the adjustable mold. Fig. 6 is a plan view seen from below and without the mold operating and adjusting levers. Figs. 7, 8 and 9 represent diagrammatically front views illustrating the relative positions of the mold forming walls the attachments, Fig. 7 corresponding to the position of Fig. 1, Fig. 8 being a view at right angle to Fig. 7 and Fig. 9 being a view at right angle to Fig. 8. Fig. 10 is a vertical sectional view of Fig. 1.

Upon the base plate *a* the posts or supports *b* are disposed between which the slotted casting plate *c* is adapted to be turned around upon its pivoting studs *d* lodged in the said

posts or supports *b*. By means of a rod or lever *l* operatively connected to a supporting bar, wedge or the like *w* the plate *c* may be retained in position. Upon the casting plate *c* four rectangularly disposed upright plates or walls *f* are mounted either directly or by means of bars *m* disposed intermediate the walls *f* and the plate *c*. Levers *e* with link connection *q*, *q'* are provided to enable the walls *f* to be moved towards and away from each other at right angle to each other. By means of suitable marginal recesses and projecting parts a close fit of the walls *f* in the closing or operating position of the mold may be insured. In the exemplification shown in the drawing one of the said walls *f* is rigidly secured to the casting plate *c*, while the other plates *f* are movable with relation thereto. The plates *f* may be guided along each other, so that they are made to enclose either a square-shaped or an oblong chamber in the operative or closing position of the parts. The arrangement may be such that two of the plates *f* may be moved by one and the same lever *e* pivoted for instance in the frame *p* and having suitable link connection *q'*. The entire combination of parts described including the casting plate *c* with the walls or plates *f* are connected in such a manner that this entire device may be turned around on the pivoting studs *d*, so that the casting plate *c* is either at the bottom or on top of the device.

The plates forming the walls of the molds are designated in the exemplification shown respectively by *f*, *f'*, *f''*, *f'''*. Of these the plate *f* is assumed to be stationary and the opposite plate *f''* is so arranged that by the operation of the two side levers *e* and *e'* it will be carried along by the movement of the side-plates or walls *f'* and *f'''* respectively engaged by the levers *e* and *e'*. These levers will therefore not only cause the separate movement of the sideplates *f'* and *f'''* at the left hand and right hand of the cavity as shown in the drawing but they will also cause the intermediate front plate *f''* to be moved with either of the side plates *f'*, *f'''*. Thus it will be obvious that by the operation of but one of the levers *e*, *e'* the size of the quadrangular mold will be changed inasmuch as

by either one of the levers two walls, that is to say the front wall and one of the side walls are displaced. After the operation of one lever and the corresponding displacement of the two walls referred to the respectively opposite lever may be operated with the result that the remaining sidewall (f^1 or f^3) is displaced together with the front wall (f^2) the arrangement being such that 10 the last operated sidewall is moved towards the first operated sidewall. The levers are so arranged and linked to the sidewalls f^1 , f^3 that one of the sidewalls, say f^1 , may be moved at right angle to the stationary rear wall f , while the other sidelever e^1 is linked to the opposite sidewall f^3 in such a manner that this latter sidewall is moved in parallelism with the stationary rear wall. With this end in view the lever e which operates 20 the left hand side wall f^1 is shaped like an elbow or a bell-crank lever and by its angularly disposed arm q it enters a socket in the side-wall f^1 and is freely movable therein, so that when the lever e is moved in the 25 direction of the arrow on its pivot plate p the side wall f^1 is moved in the angular direction with relation to the stationary wall f . On the other hand the opposite operating lever e^1 which is pivoted on its pivoting plate p^1 is 30 connected by the link q^1 to the right-hand side wall f^3 . Upon moving the lever e^1 in the direction of the arrow or in the reverse direction the side wall f^3 is thereby moved along the stationary rear wall f and in parallelism therewith.

The movement of the front wall f^2 which is adapted to partake in the movement of either of the side walls is particularly effected by means of somewhat hook-shaped extensions 40 or projections h , h' , h^2 , h^3 provided on the respective mold walls corresponding to their indices, the said extensions or projections being adapted to reach over the next adjoining side wall and to act as a guide therefor 45 in its movement. Thus the extension h which is attached to the stationary rear wall f extends downwards over the left-hand side wall f . The extension h^1 which is secured at the end of the side wall f^1 opposite the extension h extends downwards over the front wall f^2 . The latter wall is provided with a similar hook-shaped extension h^2 which extends over the right-hand side wall f^3 and the latter side wall f^3 carries a similar extension h^3 extending over the stationary rear wall f . After the side walls have been adjusted to the proper size of mold they may be locked in position by the screws r^2 and r^3 of which 55 r^2 is secured in the hook-shaped extension h^2 and is adapted for engagement with the right-hand side wall f^3 , while the screw r^3 is disposed in the hook-shaped extension h^3 secured to the right-hand side wall f^3 and may be engaged with the stationary rear wall 60 f . By this means a great variety of sizes of

the mold may be obtained. In the exemplification shown the hook-shaped extensions h , h^1 , h^2 , h^3 are screwed or otherwise secured to angular reinforcing rails or the like t^1 , t^2 , t^3 respectively attached to the corresponding side walls, in order to obviate the necessity of weakening the side walls by the insertion of the fastening screws, and to thereby considerably reduce the weight of the side walls. Stopping screws s may be employed 70 to prevent the movable side walls from becoming disengaged with the hook-shaped extensions and to limit their movement. It is obvious that by this arrangement the front wall f^2 will partake in the movement of each of the side walls f^1 , f^3 and that the stationary rear wall f acts as a guide for the movable side walls, the left-hand side wall f^1 being guided angularly at the end of the rear wall f while the right-hand side wall f^3 is guided along the front side of said rear wall. The movable front wall f^2 when moving with the left-hand side wall is guided along the right-hand side wall and when moving with the right-hand side wall is guided at the end of the left-hand side wall.

The side walls at their insides may be provided with shoulders, projections or the like shown particularly in Figs. 3, 4 and 7-9 of the drawing and adapted for the seating thereon of the pattern from which the desired simile is to be manufactured. The walls are movable upon the base plate or casting plate c which is provided with a slot, the walls of which are preferably flaring outwards so that in the reversed position of the mold this slot may be employed for the pouring in of the casting material. This slot also provides guiding means for the sprue or fin removing knife g which is operated by the handle i which is under the action of the spring i^2 and is pivoted on the stud k secured to the bottom of the base plate c of the device. By means of the connecting link i^1 the handle i operates the knife g and moves it within the casting and guide slot g^1 in the casting plate c .

The device described may be operated substantially as follows: The original article indicated at x of the drawing is introduced into the mold box and positioned upon the base plate c and between the walls thereof. The levers e and e^1 are then operated to tightly enclose and closely hug the article or pattern. Now the casting is effected by pouring liquid metal or other casting material from above into the mold box and upon the article or pattern secured therein. After the metal or casting material has become solidified or sufficiently cool the negative obtained may be withdrawn by simply opening the box by the operation of the levers. In accordance with a modified form of operation the entire device may be turned on its pivots d and by opening the side walls the negative obtained 120 125 130

may be allowed to drop out, together with the original pattern. After the negative and the original have been removed in one way or the other, the entire device is rotated 5 through 180 degrees on its pivots d . Afterwards the negative is again secured in the molding cavity and clamped in position by the operation of the levers e and e' . In this reversed position of the device, the negative 10 previously obtained constitutes the bottom of the mold cavity. The casting material is then poured into this cavity through the slot g^1 which then fills the cavity above the negative y and is allowed to solidify therein. The 15 casting sprue or fin which exists on the simile obtained and extends into the slot g^1 is then cut off by the operation of the handle or lever i . After the positive z has been finished in this manner it may be removed by the operation 20 of the levers e , e' and be allowed to drop out together with the negative y , or these parts may be removed by turning the mold box once again through 180 degrees so as to bring it on top, and by then operating the 25 levers, the positive and the negative become accessible. Thus it is possible to obtain any number of very exact copies of the original pattern by the intermediary of the negative produced in the first stage of the treatment. 30 By operating the sprue removing knife g with a short rapid and powerful movement it will smoothly cut off any excess of material so as to dispense with the necessity of difficult trimming operations for the removing of the 35 fins or projections.

While I have described my invention by way of illustration of its principles in a preferred embodiment thereof, it should be understood that modifications may be made and that no limitations upon the invention are intended other than are imposed by the scope 40 of the appended claims.

I claim:—

1. In a casting mold the combination with 45 a plurality of engageable, box-enclosing walls, slidably movable away from and towards each other, of a supporting plate secured to said walls and rotatable on a horizontal axis, an apertured part on said plate communicating 50 with the cavity between the walls and supporting means for said plate.

2. In a casting mold the combination with a plurality of engageable, box-enclosing walls, of projecting parts at the outside of said walls and engaging corresponding parts of the adjacent walls, and oppositely disposed operating means on said walls, adapted to move the walls in two different directions and at an angle to each other, and a turnable supporting bottom for said walls, and an apertured part on said bottom, adapted for communication with the mold-cavity.

3. In a casting mold the combination with a plurality of engageable, box enclosing slideable walls, of lateral, endwise stepped, angular-

lar extensions on each of said walls, adapted to be guided along the adjacent wall and engageable with the stepped end-portions thereof, operating means oppositely disposed on the walls and adapted to move the walls in different directions, a turnable supporting bottom, and supporting means for said bottom on which the walls are mounted.

4. In a casting mold the combination with a plurality of engageable, cavity enclosing walls, of exterior, lateral, endwise projecting extensions respectively secured to each of said walls, and endwise intersectingly engaging with each other, guiding means at the engaging portions of the extensions, means to secure said extensions in their relative positions, oppositely disposed levers, linked to said walls and adapted to move the extensions and the walls in different directions, a turnable bottom plate on which said walls are supported, and supporting means for said plate.

5. In a casting mold the combination with a plurality of engageable, cavity enclosing walls of exterior, lateral endwise projecting extensions respectively secured to each of said walls, and endwise intersectingly engaging with each other, guiding means at the engaging portions of the extensions, oppositely disposed levers, connected to said walls, and adapted to move them relatively to each other, a turnable, apertured molding table on which said walls are supported, and a sprue-and-fin removing knife movably disposed at the outer surface of said table below its apertured portion.

6. In a casting mold the combination with a stationarily disposed wall, and three relatively movable walls in engagement therewith, and enclosing a cavity, of exterior, angular, endwise stepped, inter-engaging extensions, respectively attached to each of said walls and overhangingly guided on the respectively adjacent wall, levers, linked to the oppositely disposed movable walls, an apertured molding table on which said walls are supported, and turnable in the vertical plane, and supporting means for said table.

7. In a casting mold the combination with a stationarily disposed wall and three relatively movable walls in engagement therewith and enclosing a cavity, of exterior, angular, endwise stepped, endwise inter-engaging extensions, respectively attached to the walls and overhangingly guided on the respectively adjacent wall, means operatively connected to the opposite movable side walls, a horizontally turnable, apertured molding table on which the walls are supported, supporting means for the table and sprue-and-fin-removing means on the table below the apertured part thereof.

8. In a reversible casting mold a bottom plate, slidably and angularly disposed up-

right enclosing walls on said plate, surrounding a molding cavity, and an apertured feeding section on the bottom plate near one of said walls.

5 9. In a reversible casting mold a bottom plate, slidably and angularly disposed upright enclosing walls on said plate, surrounding a molding cavity, substantially endwise disposed tongue-and-notch sections on said 10 walls, engaging with the adjacent walls, and an apertured feeding section on said bottom plate near one of said walls, and reversing means for said mold.

10. In a reversible casting mold a bottom 15 plate, charge-feeding means in said plate, four quadrangularly disposed, relatively angularly movable upright walls, slidably mounted on said plate and enclosing a molding and working cavity, and respectively projecting and receding inter-engaging extensions on the outer sides and on the top portions of said walls.

11. In a reversible casting mold a bottom 20 plate, reversing means operatively connected to said plate, four substantially quadrangularly disposed, relatively angularly movable upright walls, slidably mounted on said plate, moving means, linked to two opposite walls, an outwardly flaring, substantially inversely 30 funnel-shaped feeding portion in said bottom plate, and sprue cutting means movable in said feeding portion.
